US00D561707S

(12) **United States Design Patent** (10) Patent No.: **US D561,707 S**
(45) Date of Patent: **** Feb. 12, 2008**

(54) **ELECTRICAL ENERGY CONTROL SWITCH**

(75) Inventor: **Stephane Neveu**, Strasbourg (FR)

(73) Assignees: **Legrand France**, Limoges (FR);
Legrand SNC, Limoges (FR)

(**) Term: **14 Years**

(21) Appl. No.: **29/269,754**

(22) Filed: **Dec. 8, 2006**

(30) **Foreign Application Priority Data**

Jun. 12, 2006 (EM) 000545603

(51) **LOC (8) Cl.** 13-03

(52) **U.S. Cl.** D13/174

(58) **Field of Classification Search** D13/125,
D13/158-177, 184, 199; D8/310; 200/310,
200/314, 329, 4, 406, 524, 530, 532, 535-6,
200/6 A, 81 R, 5 R; D14/402

(57) **CLAIM**

The ornamental design for an “electrical energy control switch”, as shown.

DESCRIPTION

FIG. 1 is a front elevational view thereof;

FIG. 2 is a left side elevational view thereof;

FIG. 3 is a right side elevational view thereof;

FIG. 4 is a top view thereof;

FIG. 5 is a bottom view thereof; and,

FIG. 6 is a perspective view.
